[57] **CLAIM**

The ornamental design for a wiper arm for cassette cleaner for an audio player/recorder, substantially as shown and described.

DESCRIPTION

FIG. 1 is a top plan-view of a wiper arm for a cassette cleaner for an audio player/recorder showing my new design, with a cassette cleaner shown in broken lines for purposes of illustration only and forming no part of the claimed design;

FIG. 2 is a front elevational view thereof;

FIG. 3 is a rear elevational view thereof;

FIG. 4 is a right side elevational view;

FIG. 5 is a front, top and right side perspective view of

the wiper arm;

FIG. 6 is a top plan view thereof;

FIG. 7 is a bottom plan view thereof;

FIG. 8 is a front elevational view thereof; and

FIG. 9 is a right side elevational view thereof.
